CLAIM

The ornamental design for a support for a mouse, as shown and described.

DESCRIPTION

FIG. 1 is a front perspective view of a support for a mouse showing our new design;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The even length broken lines depicting the remainder of the support for a mouse in the figures show features that form no part of the claimed design. The uneven length broken lines depict an unclaimed boundary of the design.

1 Claim, 8 Drawing Sheets
